UNITED STATES PATENT OFFICE.

RAY H. MANSON, OF ELYRIA, OHIO, ASSIGNOR TO DEAN ELECTRIC COMPANY, OF ELYRIA, OHIO, A CORPORATION OF OHIO.

RELAY.

No. 927,739.

Specification of Letters Patent.

Patented July 13, 1909.

Application filed August 23, 1907. Serial No. 389,815.

To all whom it may concern:

Be it known that I, RAY H. MANSON, citizen of the United States, residing at Elyria, in the county of Lorain and State of Ohio, have invented a certain new and useful Improvement in Relays, of which the following is a full, clear, concise, and exact description, reference being had to the accompanying drawings, forming a part of this specification.

My invention relates to relays, particularly relays adapted for use in telephone systems, the object being to produce improved and simplified construction and arrangement which will decrease the size of the relay without detracting from its efficiency.

In some instances, for example, in private branch exchange installations, very little space is available for the telephone installation, and it is a very great convenience and some times a necessity to have very small relays so that a sufficient number thereof can be installed in the available space.

The relay of my invention is of such simple construction and compact arrangement that its size can be very greatly reduced without the least decrease in efficiency of operation.

In the accompanying drawings which show the construction and arrangement—Figure 1 is a top view of a relay; Fig. 2 is a side view thereof; Fig. 3 is a front view; Fig. 4 is a rear view, and Fig. 5 is a view showing the shape of the contact clips which I employ.

I provide a cylindrical core 1 which forms the sole support for all the various relay parts. The energizing winding 2 is mounted on the center of the core between the heads or end plates 3 and 4 of insulating material. The armature 5 is in the form of a flat strip, preferably of mild steel bent to the shape shown, the main part thereof extending over the coil substantially parallel to the core. The rear end extends downwardly and then horizontally, the horizontal part 6 being grooved to fit the core section 6', the whole armature structure being held in place by the screw 7, securing the end 6 to the core. The front end of the armature extends downwardly and then horizontally forwardly, the horizontal part 8 forming the pole of the armature, there being normally sufficient spring tension in the armature to hold the part 8 a sufficient distance

from the core section 9 which forms the pole of the core. The part 8 extends a distance beyond the end of the core section 9 and carries a contact point 10.

Mounted below the core section 9 is a contact spring 11 formed of flat sheet material bent to the form shown, the body part thereof being clamped between the insulating sections 12 and 13 by means of a screw 14 which threads into the section 9. The insulating block 12 has its upper face grooved out to fit the cylindrical core, and the rear edges of the insulating parts 12 and 13 and of the contact frame are square and rest against the insulating head 3, thus holding themselves rigidly in position. The front end of the contact frame extends upwardly and then horizontally forwardly, the horizontal section 13 having the platinum contact plate 16 which is disposed opposite the contact point 10, and thus when the armature pole is attracted and the armature frame moved downwardly, the contact point 10 engages contact plate 16. Threaded into the upper side of the section 9 is a brass stud 17 whose upper end is threaded to receive the spring clamping nut 18 which nut serves to adjust the normal air gap between the armature pole and the core pole. The part 19 of the stud which is of large diameter, projects a distance beyond the upper face of the core section 9 to form an abutment for receiving the armature pole upon attraction thereof and for preventing sticking of the armature pole to the core. The contact clips 20 for the various parts of the relay are mounted at the rear end of the core under the core section 6'. These contact clips are of sheet material and shaped as shown in Fig. 5, each comprising a body part 20 from the rear end of which and at one side thereof extends a clip arm 21. The front end of the body part has feet 22, 22, while from the side of the body part extends the contact clip arm 23, there being also the opening 24 through the body part for receiving a clamping screw. I employ four of these clip plates mounted in a tier below the core section 6', as best shown in Figs. 2 and 4, the alternate plates being reversed so that the clip arms 21 will appear at alternate sides to give greater space for conductors which are soldered to the ends of the clip arms. This reverse arrangement of the plates also causes alternate arrangement of the clip arms 23,

the clip arms of the first and third plates appearing at the left side and the clip arms of the second and fourth plates being at the right side.

5 Between the clip plates are the insulating strips 25, and the insulating block 26 has a rounded face to engage the core section 6' and forms a seat for the clip plates, a screw 27 passing through the insulating strips and the clip plates to securely clamp them together and to the core section 6'. The feet 22 of the clip plates and the front edges of the insulating strips and the insulating block abut against the insulating head 4 of the coil and so assist in maintaining the correct position of the clips. A clip arm 28 also extends sidewardly from the contact frame 11 at the front of the core, and this clip arm is shown connected with the clip arm 23 of the lower clip plate by means of conductor 29 which passes through openings in the heads 3 and 4. It will be noticed that there is no insulation shown between the screw 27 and the lower clip plate, and this clip plate is, therefore, in electrical contact with the core and with the armature. Contact clip arms 23 of the first and second clip plates are shown as connected with the terminals of the energizing coil. Thus to connect the relay 33 in circuit, it is necessary only to connect the various conductors with the contact clip arms 21.

The relative dimensions of the insulating heads 3 and 4 and of the clip plates is such that the contact clip arms lie entirely within the insulating heads so that when the relays are placed side by side with their insulating heads in engagement there will be no danger of electrical contact between the contact clip arms. The relays may be supported from a common mounting plate or bar 29'. The rear end 30 of the core is threaded and passes through the common supporting plate 29', insulating bushing 31 being inserted between 45 the core and supporting bar to insulate the core therefrom, a clamping nut 32 serving to clamp the core rigidly in place. Below the core opening, a rectangular opening 33 may be provided in the plate through which 50 opening the clip ends 21 may extend, and to prevent contact between the supporting plate and the clip ends the insulating strips 25 are made wider than the clip plates in order to overlap the plates, the width of the insulating strips being preferably equal to the width of the opening 33 so that the sides of the opening will also assist in holding the insulating strips in proper alinement and position.

60 It is evident that a relay built in accordance with my invention comprises a minimum number of parts and requires very little labor in the manufacture of the parts and in the assembly thereof. The parts being 65 so simple and few, the size of the relay can

be very greatly reduced. Although the size of the relay is reduced, the efficiency is in no wise impaired, and I find that the action in operation of a very small relay built in accordance with my relay is just as strong and efficient as that of larger relays in the prior art. The cylindrical pole end 9 and the flat armature pole end 8 seem to coöperate to cause concentration of the lines of force to produce a strong magnetic field and torque. 70 75

Many modifications in the construction and arrangement could, of course, be made which would still remain within the scope of my invention, and I, therefore, do not wish to be limited to the particular arrangement 80 which I have shown and described.

I desire to secure by Letters Patent the following claims:

1. In a relay, the combination of a core, an energizing winding on said core, an armature rigidly supported on said core, a contact rigidly secured to the armature and an insulated contact supported on the core and secured directly to the core by suitable fastening means, such contact adapted to coöperate with the contact on the armature. 85 90

2. A relay comprising a core, an energizing winding supported on the middle portion of the core, an armature formed of flat magnetic sheet material secured to one end 95 of the core, the other end of the core forming a pole for attracting the armature upon current flow through the energizing winding, and contact mechanism supported from the core for coöoperating with contacts on 100 the armature such armature constituting a combined magnetic return path and contact spring for the relay.

3. A relay comprising a core in the form of a cylindrical bar, an energizing winding 105 mounted along the middle part of the core, a U-shaped armature frame formed of flat magnetic sheet material, one end of the armature being secured to one end of the core, the free end of the armature being disposed 110 over the other end of the core and carrying a contact point, and a contact frame secured to the other end of the core to be engaged by the armature contact upon attraction of the armature by the core when current flows 115 through the energizing winding.

4. A relay comprising a core, an energizing winding mounted along the middle part of the core, an armature in the form of a spring plate formed of magnetic material, 120 one end of the armature plate being secured to the rear end of the core, the free end of the armature being disposed over the front end of the core to be attracted thereby upon current flowing through the winding, 125 a contact frame of sheet material secured to the front end of the core to be engaged by the armature upon attraction thereof, and contact clip plates secured in a tier below the rear end of the core and connected with the 130

winding terminals and with the armature and contact frame.

5. In a relay, a cylindrical core, an energizing winding on the core, insulating heads on the core between which the winding is confined, an armature, contact mechanism controlled by the movements of the armature, and terminal clip plates secured to the cylindrical core and having one edge abutting against one of the insulating heads.

6. In a relay, the combination of a core, insulating heads engaged in the core and set inwardly from the ends thereof to divide the core into an intermediary section and a rear and front section, an energizing winding engaging the core between the insulating heads, an armature frame of magnetic and spring material secured at one end to the rear section of the core, the free end of the armature being disposed over the front section of the core to be attracted thereby upon current flow through the energizing winding, a contact frame secured below the front section of the core to be engaged by the armature upon attraction thereof, contact clip frames secured in a tier below the rear section of the core and electrically connected with the winding terminals and with the contact frame and armature, the front edges of said clip frames abutting against the rear insulating head to thereby be rigidly held in position.

7. In a relay, the combination of a core, an energizing winding on said core, an armature rigidly supported on said core, a contact supported from said core to coöperate with a contact on the armature, and means

for adjusting said armature relatively to the core.

8. A relay comprising a cylindrical core, 40 an energizing winding on said core, an armature rigidly secured to one end of the core, and a contact on the other end of the core, such other end of the core forming a pole for attracting the armature. 45

9. In a relay, a cylindrical core, an energizing winding on the core, insulating heads on the core between which the winding is confined, an armature, contact mechanism controlled by the movements of the armature, and a plurality of terminal clip plates rigidly secured to the core by a single screw and prevented from turning by one of such heads. 50

10. In a relay, the combination of a core, 55 an energizing winding on said core, a spring armature rigidly secured to the core, a contact secured to the armature, and an insulated contact secured directly to the core, such contacts adapted to coöperate with each other when the armature is operated.

11. In a relay, the combination of a core, an energizing winding on said core, a movable armature rigidly secured to the core, a contact secured to the armature, and an insulated contact secured directly to the core, 65 such contacts adapted to coöperate with each other when the armature is operated.

In witness whereof, I hereunto subscribe my name this 25th day of July A. D., 1907. 70

RAY H. MANSON.
